UNITED STATES PATENT OFFICE.

PERCIVAL D. MOODY AND ARTHUR E. MOODY, OF NEW YORK, N. Y.;
SAID PERCIVAL D. MOODY ASSIGNOR TO SAID ARTHUR E. MOODY.

BUTTER-TRAY MACHINE.

No. 820,725.

Specification of Letters Patent.

Patented May 15, 1906.

Application filed September 6, 1904. Serial No. 223,382.

To all whom it may concern:

Be it known that we, PERCIVAL D. Moody and ARTHUR E. Moody, citizens of the United States, residing at New York, in the county of New York and State of New York, have invented certain new and useful Improvements in Butter-Tray Machines, of which the following is a specification.

This invention relates to and has for an object to provide an improved machine for manufacturing butter-trays, particularly such as are made from thin wood or veneer and are bound with sheet metal.

In the drawings accompanying and forming a part of this specification, Figure 1 is an end elevation of a form of machine embodying our present improvements. Fig. 2 is a plan view thereof. Fig. 3 is a side elevation of the same partly broken away. Fig. 4 is a perspective view of a form of product of the machine. Fig. 5 is an enlarged side view, partly shown in central section, of the forming-head. Fig. 6 is an enlarged view of a shear and forming-head for the metallic ends or binders. Fig. 7 is an enlarged view, partly shown in section, of a device for assisting in the formation of the metallic binders and for applying the same to the trays. Fig. 8 is an end view, somewhat enlarged, of the cutting-head for cutting and creasing the ends of the blanks for the trays, and Fig. 9 is a plan view of a portion of stock, showing the cutting and creasing of the blanks.

The various parts of the machine may be mounted in a compact framework, which may have a base portion (designated in a general way by 20) adapted to stand upon the floor or other convenient base. Bearings 21 will be provided in the end of the framework to support the driving-shaft 22, which is driven from a pulley 23 by a belt from some suitable source of power. (Not shown.) This shaft carries some of the cams and some of the gearing. A pair of shafts 24 25 are supported upon the respective sides of the machine, the shaft 24 by brackets 26 affording it suitable bearings, such shaft 24 having a miter-wheel 27 in mesh with a miter-wheel 28 upon the driving-shaft. The shaft 25 is similarly supported by bearing-brackets 29 and has a miter-wheel 30 in mesh with a miter-wheel 31 upon the driving-shaft.

A form of the product of the machine is represented in Fig. 4 and comprises in the

present illustration the well-known form of 55 butter-tray 40, comprising a bottom 41, sides 42, and ends which are comprised of an inside end portion 43 and overlapping portions 44, the portions of each of the ends being held together by a metallic binding 45. 60

Fig. 9 illustrates a portion of the stock, (designated in a general way by 15.) Dotted lines 46 47 illustrate the line of severance for each blank, which lines will make the edges 48 of the sides of the completed tray. In 65 such Fig. 9 the portions of the blank which enter into the tray are given the same reference characters as they bear in Fig. 4 for the purpose of comparison. At the position 49 a small triangular piece of stock is removed, 70 this being to produce the illustrated form of product, the only portion of the stock which is removed. Each blank is cut, as at 50 51, to permit the lapping of the end portions 44 44 over the portion 43. The blank is also 75 creased at 52 to permit the ready folding of the ends in the machine.

The blank 15, which, according to the present prevailing practice is made of veneer or thin wood, is fed into the machine in Fig. 2 80 from the left-hand end and passes under a cutting-die, (designated in a general way by 60,) a feed being accomplished by the following instrumentalities: There is shown a feed-table 61, having rollers 62 running upon a 85 track 63 of the machine-frame, and which carriage is normally drawn toward the end of the machine, at which the stock enters by means of a retractile spring 64. The stock is fed over this table, and a shoe 65 rests upon 90 the table or, rather, upon the stock which is upon the table during the feed movement, but is moved away from it during the backward movement or movements to gain a fresh hold upon the stock. The shoe has a 95 body portion 66, provided with ways 67, which are carried by ways 68 upon arms 69, pivoted to stub-shafts 70, carried by bearings 71, fast upon the machine-frame, and which arms are connected together at their 100 free ends by means of a pivot 72, carrying a roll 73, which may be engaged by a cam-like arm 74, fast upon a rock-shaft 75, adapted to be rocked by an arm 12, fast upon such shaft, and engaged by a cam 76, fast upon the shaft 105 95, the roll 73 being held against its actuator 74 in the present instance by means of springs 77. The body of the shoe 65 has pivoted to

it a pitman 80, which is pivoted to a crank 81 upon the shaft 14, whereby upon each rotation of the driving-shaft the feed is given a complete reciprocation. Thus the stock is 5 intermittently fed under the cutter 10, which cutter in the present instance comprises a knife 85 for removing the portion of stock at the opening 49 and also comprises cutters 86 87 for producing the incisions 50 and 51 10 and a cutter 88 for making the folding creases 52. There will be one of these cutters at each side of the machine for forming the respective ends of the blank. Each cutter-head 15 has a slide portion 90, running in ways 91 upon the machine-frame, and is retracted to its inoperative position and driven to its work in the present instance by means of an eccentric 92 and eccentric-strap 93 upon a pitman 93', connected to the slide portion 90, 20 which eccentrics are mounted upon a shaft 95, mounted in bearings upon the riser portions 96 of the machine-frame, and which shaft has a beveled pinion 97 in mesh with a bevel-pinion 98 upon the shaft 99, supported by bearing-brackets 100, and which shaft 99 has a miter-wheel 101 in mesh with a miter-wheel 102 upon the shaft 25.

The tray-forming instrumentalities are located in such a position that they will act 30 during the incising of the end portions of the blank, but in such a position that there will be a blank width between the two devices as they are in operation. This of course is merely a structural feature, but is mentioned 35 for the sake of clearness of description. The tray forming or folding head is designated in a general way by 125 and is provided with a matrix-like chamber 126, which will conform substantially to the outside of the completed 40 tray and which co-operates with a forming member 127, which will conform substantially to the inside of the tray. The member 125 is carried by a shank portion 128, which is in the nature of a slide running in 45 ways 129 upon the machine-frame and which is adapted to be retracted in the present instance by suitable coiled springs 18. The frame or slide portion 128 carries a roll 130 for the engagement of a cam 131, fast upon 50 the shaft 132, which has fast to it a gear-wheel 133, in mesh with an idler 134, which in turn meshes with a gear-wheel 135, fast upon the shaft 95.

The portions of the molding or forming 55 member which are to take the lapped portions of the box in the present instance referred to as "ends," carry members or fingers 140, pivoted at 141 to a removable block 142 and which are impelled toward the chamber 126 by springs 143, which fingers are adapted to engage the portions 43 of the blank and fold them down slightly past the predetermined finished position. Then upon the former sinking upon the internal former or 60 folder 127 the portions 44 will be lapped into

position, owing to the walls of the chamber 126, and the portions 43 will, with the fingers 140, move outwardly to their proper positions. As the head 125 is moving down toward the stock to engage the same the blank 70 for that particular box will be severed by means of a knife 144, carried by such head, and which knife may be so adjusted that it will sever the blank from the stock before any portion of it has been engaged by the 75 forming instrumentalities.

The stock may be guided to the former by guides 145, secured to each side of the machine-frame, which guides may in some instances extend back beyond the working 80 point of the former and may extend well over the same to position the blank at the inauguration of the forming operation. The guides may be bridged by a brace 146 to carry the springs 77.

While the blank which has been folded into the tray is still held between the inner and outer forming members the parts will be bound together with strips of sheet metal. The sheet metal will be applied to the lapped 90 or folded end of the trays, being bent over the edges and clamped against the sides adjacent to such edges, thus making a metallic rim on the portion of the tray at which the material from which it is made is lapped or 95 folded. In the present illustration the lapping is at the ends of the tray. For such purpose strips of sheet-metal stock (designated by 150) are fed into the machine from each side, and the feed members for such 100 stock in the present illustration are shown as duplicates one of the other, and the description of one will answer for the other. The stock is fed between a pair of feed-rolls 151 152, which are journaled in blocks 153 154, 105 carried by a frame 155, in which they may have vertical movement, the upper block being guided by a pin 156 and pressed toward the other by means of a spring 157, and one of the rolls may be provided with a ratchet 158, engaged by a pawl 159, having a portion 160 embracing the shaft 24 or 25, as the case may be, and carrying an eccentric-strap 160, actuated by an eccentric 161, upon such shaft, whereby upon the rotation of the shaft 110 the stock 150 will be fed into the machine. There is provided at each side of the machine a cutter-head 165, having a shank portion 166 in the nature of a slide supported in ways 167 and adapted to be drawn away and held 115 in its idle position by some suitable means—as, for instance, a coiled spring 168—and being provided with a shoe end 169 to be engaged by a cam 170 upon the shaft 132. Such cutter-head in the present instance comprises 120 a shear 171, mating with a shear 172 upon the table 173, over which the stock 150 is fed. The head also comprises a forming member 174, which will bend the severed stock into 125 the opening 175 of the device for bending and

130

applying such binding, which device comprises an arm 176, pivoted to a lever 177, which may be drawn to its working position by means of coiled springs 178. The arm 5 176 has a recess in which is mounted a swinging member 179, normally pressed outwardly by means of a spring 180, and which arm has an overhanging portion 181 entering a recess 182 in the member 176, and between the faces 10 of which portions 181 and 182 the opening 175 is formed. Such faces may in some instances be provided with suitable teeth to securely bite the metallic binder upon the box at suitable intervals when such faces are 15 pressed together. The movement of this securing device is controlled by means of cams 185, fast upon the shafts 24 25, and which cams run upon rolls 186, carried by the arms 177. Each arm 176 has pivoted to it a link 20 187, having a slotted end 188 embracing the shafts 24 25 and carrying rolls 189 for engagement with cams 190. After the blank for the binder has been severed and bent down into the cavity 175 the arms 177 are 25 permitted to rise and apply such bent binding-blank to the ends of the tray, after which the cams 190 will force the arms 176 inwardly, pressing the sides 181 182 of the opening 175 toward each other, the portion 30 191 of the member 179 engaging the face 192 of the lower forming member. This action will seat and fasten the binder, and thus complete the operation upon the box, after which the binder-setting device will be opened and 35 removed to its inoperative position, when the upper forming member 125 will be raised and the box ejected or placed in a position for ejection, which may be done by swinging the member 127 outwardly, it in the present 40 instance being carried by a stem portion 200, pivoted in standards 201 by means of a pivot 202, and having pivoted to it a pitman 203, which has a roll 204 upon it and is engaged by a cam 205 upon the driving-shaft 22 45 and is drawn to its work in the present illustration by means of a spring 206.

In the construction of machines embodying the present invention it will be apparent that many mechanical details may be altered 50 as occasion may require without departing from the spirit of the invention.

Having thus described our invention, we claim—

1. The combination with means for cutting flaps upon the ends of a blank, means for folding the flaps one over another to constitute the ends of a tray and to hold such folded tray in its finished form, and means for applying sheet-metal binding to such 55 folded ends comprising a clamping device having a pair of relatively movable jaws, means for shifting the clamping device into the region of the tray end, means for advancing the same to apply the binding to the tray, 60 means for actuating the clamping device to

clamp the binding upon the tray, means for shifting said clamping device away from its working position and into an idle position with its clamping device open, means for feeding a strip of sheet metal above such 70 idle position, a cutter-head embodying a cutter and a former for cutting a blank from such strip and bending the same into the jaws of the gripping member.

2. The combination with means for feeding the stock, of means for cutting blanks therefrom, means for bending the blank into a tray, means for feeding strips of sheet metal within the machine, means for cutting blanks therefrom and bending the same, and means 80 for applying such bent sheet-metal binders to the tray while held by the said forming means.

3. The combination with means to feed a strip of thin material into a machine, means 85 to score and cut the same into blanks having flaps at each end, means to fold the flaps one over another to form the end of a tray and to hold such tray at its formed position, a pair of levers pivoted below such forming device, 90 means to raise and lower the levers in unison, each of said levers carrying a gripping device comprising a pair of members movable one relative to the other and means for producing such movement, means to shift said members 95 from an idle position to the region of the tray, means to feed a strip of sheet metal above such grippers at their idle position, and a reciprocable member above such idle position, and having a shear-blade and a forming-die, 100 said shear-blade for severing a blank from such strip of metal and the die for forcing the same into the grasp of the gripper.

4. The combination with means to form a strip of thin material into a tray, and means 105 for holding such tray at its formed position, a pair of levers pivoted below such forming device, means to raise and lower the levers in unison, each of said levers carrying a gripping device comprising a pair of members movable one relative to the other and means for producing such movement, means to shift said members from an idle position to the region of the tray, means for severing a strip 110 from sheet metal, means to feed such strip 115 above such gripper at their idle position, and a reciprocable member above such idle position and having a shear-blade and a forming-die, said shear-blade for severing a blank from such strip of metal and the die for forcing the same into the grasp of the gripper.

5. In a tray-forming machine, the combination with a feed embodying a table having rollers, tracks upon the machine for the rollers, a feed-shoe adapted to engage the stock 125 upon such table, means to reciprocate the shoe, a pair of pivoted arms provided with ways, ways upon the shoe mounted thereon, means to rock the arms upon their pivot to bring the shoe into and out of engagement 130

4
with the stock, means to return the table to its initial position, a cutting-head for forming flaps upon the side of the blank to constitute the ends of the tray, a forming-head having a 5 chamber to shape the tray and having fingers to bend inwardly one flap of the blank at each end of the tray, a knife carried by such head to sever the blank from the stock, a mating former to press the blank into said chamber 10 and lap other of the flaps of the tray upon those that are bent inwardly, means to feed a stock of sheet metal toward each end of the tray, a cutting-head having a shear to sever a blank from each sheet-metal stock and having 15 means to bend the blank into form, a co-operative bending and binder applying means comprising an arm pivoted upon a lever and having an arm pivoted upon it, opposing

faces upon said arms co-operative with the bending means, means to rock the lever to 20 seat the blank upon the end of the tray, a face upon one of said arms to engage a face upon the lower former, means to press such faces together to bend the blank binder and clamp the same in position, and means to 25 rock said arm upon its pivot to bring it into the working position of the co-operative blank former, means to raise the chambered former, and means to rock the other former to eject the finished product.
